UNITED STATES PATENT OFFICE.

GEORGE GARDINER CAMPBELL, OF MILWAUKEE, WISCONSIN.

CATCH-BASIN COVER.

SPECIFICATION forming part of Letters Patent No. 430,620, dated June 24, 1890.

Application filed November 16, 1889. Serial No. 330,518. (No model.)

To all whom it may concern:

Be it known that I, GEORGE GARDINER CAMPBELL, of Milwaukee, in the county of Milwaukee and State of Wisconsin, have invented new and useful Improvements in Catch-Basin Covers; and I do hereby declare the following to be a full, clear, and exact description of said invention, reference being had to the accompanying drawings, and to the letters of reference marked thereon, which form a part of this specification.

My invention relates to improvements in that class of catch-basin covers for which Patents Nos. 204,882 and 374,393 were issued to me on June 18, 1878, and December 6, 1887, respectively.

In the drawings, Figure 1 is a vertical section of my improved device on line 1.1 of Fig. 2. Fig. 2 is a top view or plan of my improved device. Fig. 3 is a top view or plan of a slightly-modified form of my device adapted for use at the corner of a street, the device being shown in connection with so much of the sidewalk and street-pavement as is necessary to show its relation thereto.

A circular base-plate A is provided with an inner downwardly-extending flange B and an outer downwardly-extending flange C entirely around it. This base-plate and the flanges B and C form a channel beneath the base-plate, within which the top of the wall D is adapted to be received and protected. From the inner edge of the base-plate A a wall E extends vertically around a portion of the inner edge of the base-plate, and around the remainder of the catch-basin cover are located at short distances apart bars F F, extending downwardly from a top plate G at an inclination outwardly to the base-plate A. The plate G is located horizontally at the top of the wall A, and the bars F F extend at an inclination and radially from the plate G to the outer edge of the plate A. These radial bars F F are located about all that part of the cover that adjoins the pavement of the street, while the vertical wall E is about that part which abuts against the sidewalk or part of the street that is raised above the pavement alongside thereof. The bars F F serve as guards to

prevent large objects from entering the catch-basin, and also, as they are inclined and terminate at the pavement, they serve to keep the wheels of passing vehicles on the pavement and off the base-plate, or from striking any other part of the cover. An aperture or man-hole in the plate G is closed by a cover H. As the base-plate A with its flanges B and C form a channel, within which the wall D is received, the catch-basin cover is thereby held in position directly above the well or aperture within the wall D, and at the same time the top of the wall D is covered and protected from wear or injury.

The sidewalk I rests on the base-plate A throughout so much of the plate as is within the line of the sidewalk, while the pavement K is built up to and against the base-plate and flange C opposite all that part of the base-plate which is beyond the line of the sidewalk. The catch-basin cover is formed of iron and is cast integrally, except only the removable cover H.

What I claim as new, and desire to secure by Letters Patent, is—

An integral metal catch-basin cover, consisting of a circular flat horizontal base-plate, circular flanges extending downwardly vertically from the inner and outer edges of the base-plate, respectively, a vertical wall projecting upwardly from the base-plate at its inner edge and extending partially around the base-plate, a horizontal top plate at the top of the vertical wall, and inclined radial bars at a distance apart extending from the top plate to the top surface and outer edge of the base-plate about that part of the base-plate and top plate not connected together directly by the vertical wall, the bars widening radially downwardly, so that at their lower ends they are as wide as the base-plate, completely protecting it, substantially as described.

In testimony whereof I affix my signature in presence of two witnesses.

GEORGE GARDINER CAMPBELL.
